PERCY Q. WILLIAMS, OF TOLEDO, OHIO, ASSIGNOR TO THE OWENS BOTTLE COMPANY,
OF TOLEDO, OHIO, A CORPORATION OF OHIO.

GLASSWARE ANNEALING LEER.

Application filed January 28, 1927. Serial No. 164,138.

This invention relates to improvements in glassware annealing leers and particularly to a novel means for heating and introducing an annealing medium into the leer tunnel or annealing chamber.

Ordinarily, in the process of annealing glassware, the ware is conveyed through a heating zone wherein the temperature of the ware is stepped up suddenly by direct application of products of combustion or radiated heat, to the ware. Where the products of combustion come into contact with the ware, an objectionable coating or film is formed upon the ware. Further, it has been found difficult or practically impossible to obtain and maintain uniformity of temperature in the heating zone, the tendency having been to produce a high and perhaps normal temperature along the longitudinal center, while the adjacent side areas were relatively cool. This condition causes a readily apparent lack of uniformity and quality in the annealed ware and contributes appreciably to the production of defective or "off" ware.

An object of the present invention is to provide means for overcoming the above objections by introducing an annealing medium free of products of combustion into the annealing chamber, thus preventing the coating of the ware, and to provide further means for accurately controlling the temperature of the annealing medium introduced into the leer, the controlling means being such that absolutely or practically uniform temperature conditions transversely, as well as longitudinally, of the annealing zone are attainable. The means for eliminating introduction of products of combustion into the leer tunnel with the annealing medium comprises building a recuperator of units having passageways through which the medium circulates and is heated indirectly by products of combustion which are directed between and over the outer surfaces of the units. Uniform temperature conditions are obtained by providing a novel valve slide construction by which transverse sections of the recuperator may be eliminated from the path of circulation of the annealing medium and the relative rate of movement of the annealing medium through transversely spaced points of the recuperator varied.

Other objects will be apparent hereinafter.
In the accompanying drawings:

Fig. 1 is a vertical central sectional view 55 showing the relation of the recuperator and the feeding end of a leer.

Fig. 2 is a sectional view taken along the line II—II of Fig. 1.

Fig. 3 is a plan view of one of the valve 60 slides.

Fig. 4 is a detail elevation of one of the recuperator tubes, parts being broken away in section.

Fig. 5 is a fragmentary plan view showing 65 the manner in which the tube heads are relatively offset to form a wall dividing the recuperator into upper and lower chambers.

The present application embodies certain subject matter also disclosed in my co-pending application Serial Number 129,373, filed 70 August 16, 1926, but not claimed therein.

This leer includes longitudinal base members 10 formed of channel iron or other preferred units. Side walls 11 formed of suitable insulating material, rise vertically from said base members, are suitably reinforced, and have their upper ends connected together by a ceiling 12 which is also formed of any approved insulating material properly supported by a framework. An endless conveyor 13 runs over a pair of vertically spaced guide rollers 14 at the forward or feeding end of the leer, the upper reach 15 being suitably supported and serving to divide the leer into upper and lower compartments, the upper compartment constituting the ware receiving or annealing chamber 16 while the lower compartment 17 accommodates return pipes and other parts as will be understood by reference to my co-pending application, Serial No. 129,373, filed August 16, 1926.

The means for heating the annealing medium employed in annealing the glassware in the leer, comprises a combustion chamber and recuperator located at the forward end of the lower compartment 17 between the longitudinal reaches of the ware conveyor. In so far as the positioning of the heating means is concerned, it is quite obvious that under certain conditions, said means might well be located at some other point with respect to the annealing chamber to equal advantage. In arranging the recuperator in the lower compartment of the leer, side walls 18 formed of firebrick are set into the leer walls 11, the rear ends of these recuperator walls 18 being connected by a transverse wall 19 of firebrick.

The inner face of this transverse wall 19 (Fig. 1) is hollowed out providing a passageway 20 by way of which products of combustion pass from one portion of the recuperator to another as will be set forth hereinafter.

To prevent undue dissipation of heat through the transverse end wall 19, a layer of insulation 21 is arranged over the outer face of said wall, (Fig. 1). These side and end walls 18 and 19, and the layer of insulating material 21, as well as the insulating material for the side walls 18 of the recuperator, are supported upon a bottom casting 22. This casting is formed with a longitudinal passageway or chamber 23 open at one end and through which the annealing medium returns to the recuperator for reheating, and recirculation through the leer tunnel. The upper wall 24 of this casting 22 is formed with a plurality of holes 25 of uniform area, arranged in transversely aligned sets and opening into transverse ways or channels 45 (Fig. 2) formed in the top surface of the upper wall 24. These ways or channels open through opposite sides of the bottom casting 22 of the recuperator and accommodate valve slides 26 formed with openings 27, which openings decrease in diameter toward the opposite sides of the leer, said slides serving to vary and accurately control the rate of flow of the annealing medium through the openings 25 as will be pointed out.

The tube units 28 are supported upon the bottom casting 22, said units each comprising a pair of non-circular heads 29, preferably of hexagonal outline, connected by a tubular body eccentrically formed on said heads. In assembling the lower group of tubes, the passageway 30 through each tube unit is aligned with an opening 25 in the bottom casting 22. In assembling the upper group or tier of tube units, they are set upon the lower group with the tube openings in alignment, but with the abutting heads 29 dis-aligned and forming overlapping joints. This relation of the heads (Figs. 2 and 5) is such that a bonding element may be freely and easily applied in any desired amount without dropping into the spaces between the lower group of tubes, and in the final assembly the abutting heads provide a central horizontal dividing wall by which the recuperator is separated into upper and lower chambers. Such construction also materially assists in the formation of a substantial and rigid unit. The rear ends of these upper and lower chambers open into the cavity 20 in the transverse end wall 19 so that, as heretofore stated, communication between the chambers is established. The forward end of the upper chamber of the recuperator opens directly into the combustion chamber 31, into which the fuel is injected. This combustion chamber is preferably of tubular form and is supported in a suitable casting 32 extending transversely of the lower

compartment 17, said casting being supported in the side walls 11 in any approved manner. The forward end of the lower chamber of the recuperator communicates with the forward end of a flue 33, said flue extending longitudinally of the leer along the bottom of the lower chamber 17 and leading to a suitable stack (not shown) through which products of combustion are exhausted to the atmosphere.

A top casting 35 is arranged over the upper tier of tube units, said casting having a plurality of openings 36 aligned with the openings through the tube units. This top casting 35 (Fig. 2) consists of two sections 37 suitably interconnected and each formed with vertical ribs 37 supporting a portion of the upper reach of the ware conveyor 13. Filler blocks 38 (Fig. 2) are inserted between the heads of the tube units and the side walls 18 of the recuperator, giving rigidity to the structure and cooperating with the heads of the tubes in dividing the recuperator into two chambers.

The forward end of the bottom casting 22 is stepped down below the main portion so that an outlet 39 of sufficient area to permit exhaust of the products of combustion will be provided. A filler block 40 (Fig. 1) provided with vertical passageways 41, is arranged between the adjacent heads of the transverse rows of tubes over the downwardly stepped area to compensate for the lack in length on the part of the tubes, which are of standard dimensions throughout and consequently too short to extend from the top frame or casting to said area.

In order that the valve slides 26 may be utilized to control the temperature conditions transversely of the leer, as well as longitudinally of the annealing zone, the intermediate openings 27 are substantially the same area as the passageways through corresponding tubes, while the remaining openings are graduated toward the sides of the recuperator. This formation permits a relatively rapid movement of the annealing medium through the intermediate tubes, a lower rate of movement of the medium through the adjacent side tubes, and a still slower movement through the tubes adjacent the side walls, such reduction in the rate of movement resulting in an increased absorption of heat units by the annealing medium in circulating through the side tubes. Because of the possibility of accurately controlling the rate of movement of the annealing medium through these tubes as above brought out, any desired increase or decrease in the temperature of the annealing medium entering the chamber, may be had so that a substantially balanced or uniform temperature of the annealing medium transversely of the annealing zone, as well as longitudinally thereof, is readily attained and maintained. The

length and effective heating capacity of the recuperator in the path of circulation of the annealing medium may also be varied by shifting one or more valve slides so that certain of the sets of tubes are partly or entirely closed. Thus, it is evident that this form of control eliminates the unbalanced temperature in the annealing zone heretofore mentioned and contributes quite materially toward the attainment of perfection in glass-ware annealing.

Manifestly, certain minor changes may be resorted to within the spirit and scope of the appended claims.

15. What I claim is:

1. A heating unit for leers and the like comprising a recuperator, said recuperator including superposed groups of tubes, abutting heads formed on the tubes and providing a horizontally dividing wall between the groups when the tubes are assembled, means for directing products of combustion in reverse directions above and below said dividing wall over the outer surfaces of the tubes, said tubes adapted to permit passage of an annealing medium through the recuperator without contacting with the products of combustion, and means for varying the capacity of the recuperator.

20. 2. A leer comprising a ware receiving chamber, means for conveying ware through said chamber, a heating unit including a recuperator, means causing movement of an annealing medium through the recuperator, means for entirely eliminating portions of the recuperator from the path of circulation of the annealing medium, and means to cause variations in the relative rate of movement of the annealing medium through transversely spaced portions of the recuperator remaining in the path of circulation of the medium.

25. 3. A leer comprising a ware receiving chamber, means for conveying ware through said chamber, a heating unit including a recuperator, means causing movement of an annealing medium through the recuperator into said chamber, and means for varying the relative rate of flow of the annealing medium through transversely spaced areas of a selected portion of the recuperator independently of remaining portions.

40. 4. A leer comprising a ware receiving chamber, means for conveying ware through said chamber, a recuperator comprising sets of transversely aligned tubes, means for heating the tubes, means causing movement of an annealing medium through the tubes into said chamber, and valve slides having openings of varying diameters aligned with the tube passageways to vary the relative rate of movement of the annealing medium through the tubes of any selected transverse set.

45. 5. A leer comprising a ware receiving

chamber, means for conveying ware through said chamber, a recuperator comprising sets of transversely aligned tubes, means for heating the tubes, means causing movement of an annealing medium through the tubes into said chamber, and valve slides having openings of varying diameters aligned with the tube passageways to vary the relative rate of movement of the annealing medium through the tubes of any selected transverse set, said slides being shiftable to uniformly vary the quantity of annealing medium moving through the recuperator without changing the relative rate of movement of the medium through the selected set of tubes.

50. 6. A recuperator comprising a bottom casting having a longitudinal chamber opening through one end, and having a set of openings in its upper side, a plurality of tubes supported on said casting and having passageways aligned with said openings, and valve slides interposed between said bottom casting and the tubes, said slides each having a set of openings of varying diameters adapted for alignment with the passageways through the tubes to thereby vary the relative rate of movement of the annealing medium through any selected series of said tubes.

55. 7. A recuperator comprising top and bottom castings having a plurality of aligned openings, upper and lower groups of tube units arranged between said casting and having passageways aligned with each other and with the openings in said castings, said bottom casting having a chamber opening through one end and also communicating with the tube passageways by way of said openings, and means for varying the relative rate of movement of the annealing medium through the tubes of any selected transverse set.

60. 8. A recuperator comprising top and bottom castings having a plurality of aligned openings, upper and lower groups of tube units arranged between said castings and having passageways aligned with each other and with the openings in said castings, said bottom casting having a chamber opening through one end and also communicating with the tube passageways by way of said openings, and means for varying the relative rate of movement of the annealing medium through the tubes of any selected transverse set, said means comprising valve slides extending transversely of the recuperator and having graduated openings adapted at times for alignment with the tube passageways.

65. 9. In a recuperator for glass annealing leers and the like, means permitting passage of an annealing medium through the recuperator, means for rendering a portion of the recuperator inactive, and means whereby the relative rate of movement of the annealing medium through transversely spaced

- points of the remaining active portion of the recuperator may be varied.
10. In a recuperator for glass annealing leers and the like, means permitting passage of an annealing medium through the recuperator, means for rendering a portion of the recuperator inactive, means for changing the relative capacity of selected longitudinally spaced portions of the remaining active area, and means whereby the relative rate of movement of the annealing medium through transversely spaced points of the remaining active portion of the recuperator may be varied.
15. 11. A recuperator unit comprising a pair of spaced heads of non-circular peripheral contour having eccentrically disposed aligned openings, and a body inter-connecting said heads and having a passageway aligned with said openings.
12. An annealing leer comprising in combination an annealing chamber extending lengthwise of the leer, means for introducing heated air into said chamber at different points transversely thereof and causing said air to circulate lengthwise of said chamber, and adjusting means for adjusting the relative temperature of the air entering at different points transversely of said chamber.
13. An annealing leer comprising in combination an annealing chamber extending lengthwise of the leer, means for introducing heated air into said chamber at different points transversely thereof and causing said air to circulate lengthwise of said chamber, and means by which the air entering said chamber adjacent the side walls thereof may be raised to a higher temperature than the air entering at intermediate points.
14. In an annealing leer, the combination of an annealing chamber extending lengthwise of the leer, a series of tubes through which heated air is conveyed to said chamber, said tubes communicating with said chamber through a series of openings arranged transversely of the chamber, and means for pro-
- viding a lower temperature and more rapid flow of air through the intermediate openings of said series than through those nearer the outer side walls of said chamber.
15. In an annealing leer, the combination of an annealing chamber extending lengthwise of the leer, a series of tubes through which heated air is conveyed to said chamber, said tubes communicating with said chamber through a series of openings arranged transversely of the chamber, and adjusting means for controlling and adjusting the relative temperature of the annealing air at different points transversely of the leer by adjustably controlling the relative temperature of the air passing through the different openings of said series.
16. A leer comprising an annealing chamber, a unit including a recuperator and a heater arranged below the forward end of the chamber, means supplying air through the recuperator to the chamber, and means for varying the effective heating capacity of the recuperator.
17. A leer comprising an annealing chamber, a unit including a recuperator and a heater arranged below the forward end of the chamber, means supplying air through the recuperator to the chamber, and manually controlled valves operable to vary the effective heating capacity of the recuperator.
18. A leer comprising an annealing tunnel, a heating unit below the forward end of the tunnel, a vertical tube recuperator associated with said unit and opening into said annealing tunnel through the floor of the latter, means causing continuous recirculation of atmospheric air through the recuperator and predetermined portions of the tunnel, and means including slide valves for eliminating certain of the recuperator tubes from the path of circulation of air.

Signed at Toledo, in the county of Lucas and State of Ohio, this 24th day of January, 1927.

PERCY Q. WILLIAMS.
